UNITED STATES PATENT OFFICE.

HIPPOLYTE F. MENGDEN, OF HOUSTON, TEXAS.

MOP.

Application filed May 31, 1927. Serial No. 195,342.

This invention relates to new and useful improvements in a mop.

One object of the invention is to provide, in a mop, novel means for securing the thrums, of which the mop head is composed, to the handle.

A further feature of the invention resides in the provision of a mop, the thrums composing the head of which are secured to the handle in a novel manner.

With the above and other objects in view the invention has particular relation to certain novel features of construction, arrangement of parts, and use, an example of which 15 is given in this specification and illustrated in the accompanying drawings, wherein:—

Figure 1 shows a side elevation of the complete mop.

Figure 2 shows a longitudinal sectional view of the mop in partially completed condition.

Figures 3 and 4 show plan and edge views respectively of the thrum securing band employed, and

Figure 5 shows an elevation thereof.

Referring now more particularly to the drawings wherein like numerals of reference designate similar parts in each of the figures the numeral 1 designates the mop handle 30 to one end of which the mop head is secured, said head being designated generally by the numeral 2. The thrums are secured to the handle end by means of an inside band 3 and an outside band 4, said bands being of similar construction. Each band is composed 35 of an elongated metallic strip reduced at one end forming a relatively narrow tongue 5. At the other end each strip is formed with an eye 6, preferably triangular in form 40 with one apex facing toward the corresponding end of the strip. The strip is formed into an encircling band by bending it in circular form and inserting its tongue 5 through its eye 6 and then bending the tongue back into parallel relation with the body of the band, the bend of the tongue 45 being gripped by the converging sides of the eye 6 so as to hold the adjacent ends of the band securely together.

In constructing the mop the thrums are arranged in substantially parallel relation in a body and they may be retained in such position temporarily by the retaining ring 50 as 8. The handle is then inserted lengthwise into one end of the body of the thrums 55 thus arranged, as illustrated in Figure 2 and

the securing band 3 is then drawn tightly around the thrums some distance back from the adjacent end of the handle. For the purpose of additionally securing the band 3 to the handle one or more nails as 9 may be driven through the corresponding perforations as 10 of the band and into the handle. The free ends of the thrums into which the handle has been inserted are then looped around the band 3, as indicated in Figure 1 and an outside securing band as 4 is then secured around the entire head of the mop, as shown in Figure 1, said outside band 4 being preferably located between the 70 inside band 3 and the adjacent end of the handle 1. The outside band is then secured in position by passing its tongue 5 through the corresponding eye 6 and bending it back as hereinabove explained and as shown in Figures 1 and 5. This outside band may be secured to the handle 1, if desired, by a similar use of the nails, as 9, as hereinabove explained.

By the use of the securing bands 3 and 4 80 of the type hereinabove described and arranged and secured in position as stated a mop can be constructed more quickly and cheaply than by methods now in common use and a more durable article at the same 85 time produced. The bands 4 are made of different lengths between the eye 6 and the shoulders 11 formed by reducing the opposite end of the band, these lengths depending on the size of the mop to be made and in drawing the band around the thrums of the mop head the tongue 5 is drawn through the corresponding eye 6 until the shoulders 11 abut against the opposing sloping sides 90 of said eye thus assuring the required tension on the band, and a uniform tension on the bands of different mops constructed.

What I claim is:—

1. In a mop a securing thrum band formed of a strip of metal having an eye at one end 100 with sides which converge outwardly, the other end of the band having a tongue adapted to be looped through said eye and gripped by the converging sides thereof.

2. A securing band formed of a strip of 105 metal having an eye at one end whose sides converge outwardly, a tongue narrower than the band at the other end thereof said tongue being adapted to be looped through said eye said converging sides forming 110 means for gripping the tongue.

3. A securing band formed of a strip of

metal having an eye at one end whose sides converge outwardly, a tongue narrower than the band at the other end thereof, said tongue being adapted to be looped through said eye said converging sides forming means for gripping the tongue, said band being provided with a perforation adjacent said eye.

4. A securing band formed of a long strip 10 of metal with an eye in one end of said

band having sides which converge outwardly, said eye being of a width to receive the other end of the band and said converging sides forming gripping means for said other end when the same is inserted there- 15 through.

In testimony whereof I have signed my name to this specification.

HIPPOLYTE F. MENGDEN.
